United States Patent

Des. 236,778
Patented Sept. 16, 1975

236,778

COMBINED BAG STORAGE AND FILLING RACK

Arthur Adolph Thiere, West Covina, and Raymond
Harold Sanders and George Edwin Johnson, Ontario,
Calif., assignors to Standun, Inc.

Filed Jan. 21, 1974, Ser. No. 435,297

Term of patent 14 years

Int. Cl. D6—99

U.S. Cl. D6—85

Fig. 1.

Fig. 2.

Fig. 5.

Fig. 3.

Fig. 6.

Fig. 4.

FIG. 1 is a perspective view of a combined bag storage and filling rack showing our new design, illustrative use thereof being shown in phantom lines;

FIG. 2 is a top plan view;

FIG. 3 is a front elevational view;

FIG. 4 is a bottom plan view;

FIG. 5 is a side elevational view; and

FIG. 6 is a rear elevational view.

We claim:

The ornamental design for a combined bag storage and filling rack, as shown and described.
